UNITED STATES PATENT OFFICE.

WILLIAM B. CRENSHAW, OF WATSON, WEST VIRGINIA.

HAT-BOX.

1,271,542.

Specification of Letters Patent.

Patented July 9, 1918.

Application filed October 9, 1917. Serial No. 195,630.

To all whom it may concern:

Be it known that I, WILLIAM B. CRENSHAW, a citizen of the United States, residing at Watson, in the county of Marion and 5 State of West Virginia, have invented certain new and useful Improvements in Hat-Boxes; and I do hereby declare the following to be a full, clear, and exact description of the invention, such as will enable others 10 skilled in the art to which it appertains to make and use the same.

This invention relates to boxes and more particularly to hat boxes and the primary object of the invention is to provide an improved hat box which has an opening in the front thereof as well as ordinary top closure, so that the contents of the box can be removed therefrom through the front thereof and thus eliminate the necessity of taking 20 the box from the shelf.

Another object of the invention is to provide an improved box having the ordinary top closure and a pivoted front closure and having means to prevent accidental removal 25 or opening of one of the closures while the other closure is being opened.

A further object of the invention is the provision of an improved draw spring which is so associated with the body that the same 30 can be so manipulated as to hold either one of the closures against removal.

A still further object of the invention is the provision of a hat box of the above character, which is durable and efficient in use, 35 one that is simple and easy to construct, and one that can be placed upon the market at a reasonable price.

With these and other objects in view the invention consists in the novel construction, 40 arrangement and formation of parts as will be hereinafter more specifically described, claimed, illustrated in the accompanying drawings, forming a part thereof in which:

Figure 1 is a perspective view of the improved hat box,

Fig. 2 is a transverse vertical section of the same, and

Fig. 3 is a horizontal section taken on the line 3—3 of Fig. 2.

Referring to the drawings in detail wherein similar reference numerals designate corresponding parts throughout the several views, the numeral 1 generally indicates the improved hat box which includes side walls 55 2 and 3 respectively, the rear wall 4, the bottom wall 5 and the front wall 6. The

front wall 6 is pivoted to the bottom 5 by means of a hinge 7 which is preferably formed of flexible material such as fabric and preferably glued in position. The front 60 wall 6 is so formed as to fit snugly in between the side walls 2 and 3. The side edges of the front wall 6 are provided with guide flanges 8 which extend the entire height of the wall and are connected at 65 their upper portions by a connecting strip 9. The guide flanges 8 and the connecting strip 9 form means for guarding against the entrance of dust into the box. A flexible strip 10 is secured to the central portion of 70 the front wall 6 and forms a tab whereby the front wall can be swung downward on the hinge 7.

A closure 11 is provided for the top of the box and consists of the rectangular plate 12 75 having downwardly extending flanges 13 formed on its edges. The front flange 13 is made separate from the rest of the flanges and the same is connected to the front edge of the plate 12 by means of a hinge 14. The 80 hinge 14 is preferably made of flexible material similar to the hinge 7, so that the front flange can be drawn upward when the front wall 6 is desired to be thrown open. A U-shaped bail 15 is pivoted to the side 85 flanges 13 of the top closure 11 and forms means for holding the closure 11 on the box and also prevents the front wall 6 from being accidentally opened. The free ends of the legs 16 of the U-shaped bail 15 are bent 90 inwardly toward each other as at 17 and the inwardly bent ends are received in openings 18 formed in the side flanges 13 of the top closure 11. By this construction the U-shaped bail 15 is pivotally secured in place. 95 The bight portion 19 of the bail 15 is bent slightly inwardly, so as to frictionally engage the front flange 13 and force the same rearwardly, so as to hold the top closure 11 in frictional contact with the front wall 6 100 and thus prevent the accidental displacement of the top closure. When the bail 15 is thrown downward so as to position the bight portion 19 in engagement with the front flanges 13, it is impossible to open the 105 front wall 6 as the front flange 13 engages the upper edge of the same.

An endless flexible cord 20 is provided for engagement with the top closure 11 and the front walls 6 and is so arranged as to 110 prevent the accidental opening of one closure, while the other is being manipulated.

A pair of spaced openings 21 are formed in the central portion of the side walls 2 and 3 adjacent the upper edge thereof and threaded through the openings in the end-
5 less flexible member 20. Each of the open-
ings 21 has a reinforcing member 22, which
provides a guard for the edge of the opening
and allows the endless cord 20 to readily
slide through the openings. One portion 23
10 of the flexible member 20 is positioned so as
to engage the top closure 11 and the oppo-
site portion 24 is positioned, so as to en-
circle the front wall 6.

In operation of the improved hat box
15 when it is desired to open the front wall 6
the flexible endless cord 20 is pulled out and
the portion 24 will resume a position as
shown in Figs. 1 and 2 and the bail member
15 is then thrown upward, which will allow
20 the front flange 13 to be swung upward and
by pulling on the tab 10 the front wall 6
can be readily swung on the hinge 7. When
the flexible member 20 is pulled so as to
open the front wall 6 the upper portion 23
25 thereof is drawn into engagement with the
top closure 11 which prevents the acciden-
tal removal thereof. When it is desired to
remove the top closure 11, the upper portion
23 of the flexible member 20 is pulled which
30 draws the flexible member through the re-
inforcing members 22 and positions the
lower portion 24 in tight engagement with
the front wall 6 and prevents the acciden-
tal opening of the same. When the upper
35 portion 23 of the flexible member 20 has
been pulled out of engagement with the
top closure 11 the same can be readily re-
moved.

A reinforcing strip 25 extends from the
40 front upper edge of the side wall 2 to the
opposite front edge of the side wall 3 and
forms means for preventing the side walls
from spreading at the front portion thereof
and also provides a rest for the front por-
45 tion of the top closure.

From the foregoing description it can be
seen that an improved hat box is provided
which has an opening in its front wall and
an opening in the upper wall and has means
50 to absolutely prevent the accidental open-
ing of either one of the closures for the
openings, when one of the same is being
manipulated.

In practice, I have found that the form
55 of my invention, illustrated in the accom-
panying drawings and referred to in the
above description, as the preferred embodiment,
is the most efficient and practical; yet
realizing the conditions concurrent with the
60 adoption of my device will necessarily vary,

I desire to emphasize the fact that various
minor changes in details of construction,
proportion and arrangement of parts may
be resorted to, when required, without sacri-
ficing any of the advantages of my inven- 65
tion as set forth.

What I claim as new is:—

1. A hat box comprising a substantially
rectangular casing having an opened front
and top, a removable closure for the top, a 70
pivoted closure for the front, and an endless
flexible member slidably associated with the
casing for engaging either the front or top
closure to prevent the accidental opening of
one closure, while the other is being opened. 75

2. A hat box comprising a bottom, rear
and side walls, a front wall pivotally se-
cured to the front edge of the bottom wall,
and a removable cover for the top of the
box, said side walls each having a pair of 80
spaced apertures formed therein, and an
endless flexible member slidably mounted in
the openings, said endless member being
adapted to engage either the front closure
or the top cover, as and for the purpose 85
specified.

3. A hat box comprising a bottom, rear
and side walls, a front wall pivotally se-
cured to the bottom wall of the front edge
thereof, a removable cover for the top of 90
the box, said cover having downwardly ex-
tending flanges formed on the side edges for
engaging the upper edges of the rear, side
and front walls, the front flange of said re-
movable cover being pivotally secured there- 95
to, and means pivotally carried by the re-
movable cover for engaging said front
flange, as and for the purpose specified.

4. A hat box comprising a bottom, rear
and side walls, a front wall pivotally se- 100
cured to the bottom wall at the front edge
thereof, a removable cover for the top of
the box, said cover having downwardly ex-
tending flanges formed on the side edges
thereof for engaging the upper edge of the 105
rear, side and front walls, the front flange
of said removable cover being pivotally se-
cured thereto, and a U-shaped bail mem-
ber pivotally secured at its free ends to the
side flanges of the cover, the bight portion 110
of said U-shaped bail being arranged to
engage the pivoted front flange, as and for
the purpose specified.

In testimony whereof I affix my signa-
ture in presence of two witnesses.

WILLIAM B. CRENSHAW.
